UNITED STATES PATENT OFFICE.

ELROY L. ROGERS, OF WAKEFIELD, MASSACHUSETTS.

CATCHER'S GLOVE.

SPECIFICATION forming part of Letters Patent No. 528,343, dated October 30, 1894.

Application filed July 12, 1894. Serial No. 517,285. (No model.)

To all whom it may concern:

Be it known that I, ELROY L. ROGERS, of Wakefield, in the county of Middlesex and State of Massachusetts, have invented certain 5 new and useful Improvements in Base-Ball Mitts, of which the following is a specification.

This invention relates to the padded mitts or gloves employed by base-ball players, particularly catchers, and has in view an improved arrangement for closing the mitt so that it can be opened when desired for the purpose of rearranging the padding or taking out old and putting in new padding. It is well known 10 that the hard usage to which a glove of this character is subjected causes the padding to become disarranged, and also matted so as to require rearrangement and replenishment. It is therefore desirable that the interior of 15 the mitt will be accessible, and my invention is directed toward providing closing devices which will allow access to the padding and which will present no unyielding protuberances, such being objectionable for obvious 20 reasons.

An embodiment of the invention is illustrated in the accompanying drawings which form part of this specification.

Figure 1 shows a perspective view of the 25 mitt closed. Fig. 2 shows a section on line 2—2 of Fig. 1. Fig. 3 shows a perspective view of the glove opened. Fig. 4 shows the locking piece detached.

The general construction of the mitt is that 30 commonly employed, its pad-portion comprising a palm, *a*, and back, *b*, each made of a single piece of leather cut out in the proper shape, a connecting edge-strip, *c*, and padding, *e*, filling the space between the palm and back.

40 The usual pocket for the hand of the wearer is attached to the back-piece, *b*, a portion of it only showing in Fig. 1, and designated by the letter, *d*. This pocket is not shown in full as it does not differ from those commonly found 45 in this class of gloves.

In carrying out my invention the edge strip, *c*, is divided for a considerable distance around the inner side of the mitt, as shown at *e'*, the 50 dividing slit extending from a point some- what back from the end of the thumb portion of the mitt on the outer side, well around to

the opposite side of the mitt, so as to allow ample opening of the mitt for access to the interior thereof. The leather of the edge strip at the ends of the dividing slit works as 55 a hinge in the opening of the mitt.

Along each side of the dividing slit, a strip of leather *f* is secured by stitching or otherwise, and each strip is provided with a number of elongated loops *f'* separated from each 60 other, each loop being preferably integral with the strip on which it is formed. The loops on each strip alternate in position with those on the other strip, so that the loops may be interlocked and brought into alignment 65 when the mitt is closed. A locking-piece or stringer *g*, which is preferably a rounded strip of leather, is run through the aligning loops, and its ends properly secured. I have here shown the ends of this locking-piece fastened 70 by means of pieces of string *h* attached to them and wound around buttons *h'* riveted to the edge-strip *c*; but it is evident other means might be employed for accomplishing the same purpose. 75

It will be seen that my method of closing the mitt provides a perfectly pliable joint, and there are no unyielding protuberances, as metal fastenings. Moreover, the alternating loops and the locking-strip cover the dividing slit, and there is no possibility of the padding protruding through this slit. 80

The locking-piece or stringer should be sufficiently stiff to prevent lateral movement of the loops or eyes, and sufficiently flexible to 85 conform to the curvature of the edge of the glove.

What I claim as my invention is as follows:

1. In a catcher's mitt or glove, a pad-portion comprising a back and a front or palm piece, an edge-strip connecting the back and front pieces and formed with a dividing slit, strips of pliable material fastened to the said edge-strip along opposite sides of the slit and having elongated loops alternately arranged 95 so that all may be brought into alignment, and a round leather locking stringer passing through the aligning loops.

2. In a catcher's mitt or glove, a pad-portion comprising a back and a front or palm 100 piece, an edge-strip connecting the back and front pieces and formed with a dividing slit,

strips of pliable material fastened to the said edge-strip along opposite sides of the slit and having elongated loops alternately arranged so that all may be brought into alignment,

5 a round leather locking stringer passing through the aligning loops and having fastening strings at its ends, and buttons fastened to the edge-strip of the glove and adapted to receive the said fastening strings.

In testimony whereof I have signed my name to this specification, in the presence of two subscribing witnesses, this 10th day of July, A. D. 1894.

ELROY L. ROGERS.
